SIGNAL

Filed Sept. 6, 1927

UNITED STATES PATENT OFFICE.

GEORGE W. RAPP, OF LOUISVILLE, KENTUCKY.

SIGNAL.

Application filed September 6, 1927. Serial No. 217,780.

My invention relates to signals and has for its primary object to provide an automatically operable signal for indicating any slackening of speed of motors, engines, and moving vehicles, such as automobiles, trains or street cars,—the signal in the latter instances serving to warn a vehicle approaching from the rear of a slackening in the speed of the signal-equipped vehicle in front.

10 The invention also has for an object to provide a very simple electrically operated and speed control signal of this kind which will be of inexpensive construction, positive in operation and which will not be actuated 15 when the vehicle increases in speed.

Other objects and advantages of the invention will be apparent as the description proceeds, and in order that the same may be better understood reference is had to the accompanying drawing which illustrates the 20 now preferred forms of the invention.

In the drawings, wherein the same reference characters designate the same parts in all views,

25 Figure 1 is a view partly in elevation and partly in section and illustrating a signal embodying my invention;

Figure 2 is a section on line 2—2 of Figure 1;

30 Figure 3 is a fragmentary perspective view of a contact post;

Figure 4 is a front elevation of a modified form of the invention;

Figure 5 is a fragmentary perspective view 35 of a detail; and

Figure 6 is a cross-section similar to Figure 2 but showing the modified form of the invention.

Referring specifically to the drawings, 1 40 designates generally a governor which is journaled upon shaft 2 which may be secured to any suitable support. The upper collar 3 of the governor is fixed against axial movement, being supported on a shoulder of the shaft.

45 A gear 4 adjacent collar 3 and driven by a bevel gear 5 serves to drive the governor 1. The bevel gear 5 is journaled in a suitable bearing of support 6 and is driven by a flexible drive connection 7 which is geared as at 8 to the gear 9 of the speedometer cable 10.

The lower collar or sleeve 11 of the governor has attached thereto the lower ends of the governor arms 12 said sleeve receiving a collar 13 secured by a nut screw 14 which 55 serves to clamp the metal contact carrying

arms 15 in place and against the shoulder of sleeve 11.

In the form of invention shown in Figure 1 a fibre bar 16 is provided at right angles to arm 15, which is bifurcated as at 15^a to engage the sides of bar 16. The fibre bar 16 has its edge facing the bight portion of bifurcation 15 formed with tooth-like serrations 17, the slanted surfaces 17^a of which have inserted therein contacts 17^b which are connected as at 18 to a current carrying wire 19 running longitudinally of the fibre bar 16. Electrical connection is had from wire 19 to battery B by a binding post 20 and wire 21. The other side of the battery is connected by wire 22 to the binding post 23 of an illuminated lamp box signal 24. The other binding post 25 of the signal 24 has its wire 26 suitably grounded as indicated at 26^a. A bolt 27 secures the contact finger 28 in place on 75 governor arm 15 and said finger may be adjusted by set screw 29. The outer end of finger 28 is drawn thin to define a very flexible contact point which is adapted to engage the contacts 17^b on the slanting sides of the 80 teeth 17 when the arm 15 of the governor descends when the speed of the vehicle slackens. It is, of course, to be understood that when the speed of the vehicle increases and the arm 15 is drawn up the end of the 85 contact member 28 will engage the horizontal sides of the teeth 17 and jump over the contacts 17^b which are disposed upon the slanting surfaces 17^a of such teeth.

By this arrangement the circuit of the signal 90 24 will be closed only when the speed of the vehicle slackens. The very thinly drawn end of the contact element 28 coupled with the slightly upturned shape thereof tends to cause said arms to disengage from the contact 95 17^b when the speed of the vehicle is maintained at a uniform rate after a decrease in speed. Thus the signal will only be on,—to all intents and purposes,—when the vehicle is decreasing speed.

100 A modified form of the invention is shown in Figure 4 wherein a fibre block 30 is provided corresponding to block 16 and which fibre block 30 is rectangularly cored out as indicated at 31 and has provided therein adjacent one side, with an upstanding metal post 32 which has at its lower end a binding post 33 for securing the metal post in the block 30 and which is connected by wire 34 to the battery B. The wire 34 corresponding 110

to the wire 31 in the form of the invention already described. The form of invention shown in Figure 4 differs from the previously described form only in the block 30 and formation of the contact finger arm 35 which is carried by the arm 15 of the governor. The contact finger 35 which is secured to the governor arm 15 is swingable on the bolt 27 as a pivot and the end of the contact member 35 is rounded, as at 35^a in Figure 4. The contact carrying post or strip 32 cooperates with the back of the fibre block 30 in supporting diagonal strips 37 having oppositely curved ends 38 and 39. The upper surfaces of the ends 39 of the members 37 have contact plates 39^a which of course make a contact with the upper standing post 32. The ends 38, 39 are sufficiently flexible to permit the circular end 35^a of the contact element 35 to force its way past the same, reference being had to the arrows in Figure 4 which indicate the direction of movement of the contact member 35 with the governor arm 15. By reference to Figure 4 it will be evident that when the governor arm 15 is moved upwardly the contact end 35^a will engage the fibre lower portion of one of the diagonal elements 37 passing from the end 39 diagonally upward and past the end 38. So long as the speed of the vehicle increases the contact end 35 will pass upwardly at the right of the block 30 and between the side thereof and the ends 38 of the diagonal members. However, as soon as the speed of the vehicle slackens down and the arm 15 lowers the contact end 35^a will be engaged by the subjacent end 38 of one of the diagonal members 37 (which end 38, by the way, is relatively inflexible in a downward direction) thus causing the contact end 35 to slide transversely swinging on 27 as a pivot and to engage the contact portions 39^a at the lower end of elements 37, thus closing the circuit of the signal. When the speed of the vehicle increases the contact end 35^a, of course, will engage the ends 39 of the diagonal element and the contact end 35 will be moved upwardly and the circuit will be broken.

Having thus described my invention what I claim as new and desire to secure by Letters Patent is:—

1. In an electric signal, a speed responsive governor, an arm carried thereby, a post of non-conducting material arranged at right angles to said arm, said arm having a bifurcated end embracing said post whereby the latter guides the arm in its movement, a contact finger extending between the sides of the bifurcated end of said arm, contacts on said post adapted to be engaged by said finger when the arm moves in one direction, and means associated with said post for preventing said finger from engaging said contacts when the arm moves in the opposite direction.

2. In an electric signal comprising a sig-

nal element and circuit therefor, a movable speed controlled contact in said circuit, a series of insulated contacts in said circuit and over which said speed controlled contact plays when moved in one direction, supporting means for said insulated contacts, and diagonally disposed abutments carried by said contact supporting means for engaging the speed controlled contact when it is moved in the other direction to divert same laterally to prevent contact with said insulated contacts.

3. A signal circuit closer for speed responsive elements comprising an arm carried by said speed responsive element and extending laterally thereof, a block extending in the direction of travel of said speed responsive element, a guiding connection between the end of said arm and said block, a plurality of spaced circuit contacts carried by said block, a series of diagonally disposed shoulders protruding from the surface of said block and to the upper surface at one end of which shoulders said contacts are secured, a laterally movable contact member carried by said arm, said block having side flanges spaced from the ends of said shoulders whereby to maintain the contact element of said arm in a position to be intercepted by the ends of said shoulders, the ends of said shoulders being relatively flexible, said laterally movable contact of said arm being adapted to play over said block contacts when said speed responsive element and arm are moved in one direction, and said shoulders being adapted to engage said contact to divert the same laterally and along the opposite ends of said shoulder when the speed responsive element is moved in the opposite direction.

4. The combination set forth in claim 3, and the ends of said shoulder remote from the contact being adapted to intercept said arm carried contact element when the speed responsive element moves in the first mentioned direction whereby to swing arm carried contact element to a position to engage said contacts during the period of movement of said speed responsive member and arm in the direction first referred to.

5. A switch comprising a carrier, an arm extending laterally from said carrier, a block having a guiding connection with the ends of said arm, a laterally movable contact member carried by said arm and having its end disposed adjacent the opposed surface of the block, a series of spaced diagonal shoulders protruding from the face of said block opposite the end of said arm, said shoulders having extremities at one end flexible in one direction and extremities at the other end flexible in the opposite direction, said block having a marginal flange spaced from the ends of said shoulders, and adapted to maintain the contact element of

said arm in a position to engage the ends of said shoulders in the movement of the speed responsive element and arm, contact elements disposed upon one surface of said shoulder 5 at one end thereof and lying in alined series, the ends of said shoulders being inflexible in the direction of said contact surfaces whereby the contact element of said arm when the latter is moved in one direction will be diverted laterally away from said contacts, the opposite ends of said shoulders being yieldable in said direction of movement of the arm to permit said contact to pass thereby but nonyieldable in the opposite direction 10 whereby to direct said arm carried contact in the direction of said shoulder contacts upon movement of the arm and its contact in the reversed direction.

6. A circuit closer for speed responsive

elements comprising an arm carried by the speed responsive element, a guide block extending in the direction of travel of said speed responsive element, said arm having a bifurcated end slidably engaging opposite sides of the block to provide a guiding connection between said arm and said block, a contact member carried by said arm, spaced contacts carried by said block, and over which said contact element is adapted to play on the movement of the speed responsive element and arm, in one direction, and means carried by said guide block for deflecting said arm carried contact element clear of said block contact when the arm moves in the opposite direction. 15 20 25 30 35

In testimony whereof I affix my signature.

GEORGE W. RAPP.
